[57] CLAIM

The ornamental design for an aluminum can cruncher, substantially as shown and described.

DESCRIPTION

FIG. 1 is a reduced perspective view of an aluminum can cruncher showing my new design;

FIG. 2 is a top plan view thereof;

FIG. 3 is a front elevational view thereof;

FIG. 4 is a side elevational view taken from the right of FIG. 1; and

FIG. 5 is a fragmentary partial enlarged sectional view taken in the direction of the arrows on line 5—5 of FIG. 4.

FIG. 1

FIG. 2

FIG. 3

FIG. 4

FIG. 5
